EUGÈNE HENRI TARTRAIS, OF MAISONS-LAFFITTE, FRANCE.

FUEL PUMP FOR INTERNAL-COMBUSTION ENGINES.

Application filed July 16, 1921. Serial No. 485,233.

To all whom it may concern:

Be it known that I, EUGÈNE HENRI TARTRAIS, citizen of the French Republic, residing at Maisons-Laffitte, Seine-et-Oise, in the 5 Republic of France, have invented new and useful Improvements in Fuel Pumps for Internal-Combustion Engines, of which the following is a specification.

This invention relates to improvements in 10 pumps which are employed particularly for injection of liquid fuel in internal combustion engines. The invention relates more particularly to the method of regulating the output, and secondarily to lubricating and 15 to fluid-tight devices which result from the arrangements adopted for effecting the said regulation.

The accompanying drawings show by way 20 of example an embodiment of this invention in the case of a two cylinder two-cycle engine. Two separate pumps are in fact employed in this case, but these are combined in a single device and are actuated by a common shaft which rotates at the same speed 25 as the engine.

In said drawings:

Fig. 1 is a vertical longitudinal section on the axis of the device, showing only one pump in section.

30 Fig. 2 is a vertical cross-section through the axis of a pump, this being the pump which is not shown in section in Fig. 1.

Fig. 3 is a horizontal section through the upper casing.

35 Fig. 4 is a horizontal section through the racks actuating the regulating stop-pieces.

Fig. 5 shows the profiles of the cams.

Fig. 6 is a sectional view of the fuel admission cock.

40 1 (Fig. 1) indicates the actuating shaft which is connected with the engine by a coupling device, not shown. Upon the said shaft is secured by means of a key 7 engaging in a key way 7^a, a sleeve 5 which is pro-

45 vided with a helical slot cooperating with a stud 4. This latter is mounted upon a bushing 3 secured to a cam shaft 2. A fork 8 secured to a rock shaft 8^a provides for the lengthwise movement of the sleeve 5 during

50 the running of the apparatus, in such manner as to obtain a relative angular displacement of the two shafts 1 and 2 by means of the helical groove, whereby the moment of the injection may be varied by the outer lever 45 (Fig. 4) which is secured upon the rock shaft 8^a.

The pistons 13 of the pump are actuated by the cams 9 mounted on the shaft 2 through the intermediary of the pusher rod 11 slideable in the guiding members 12. Each 60 piston is slideable in a guiding member 59 and is provided with a return spring 14.

Each of the fuel suction valves 16 which is guided by a cap 18, is actuated by a cam 10 through the intermediary of a pusher 65 rod 22 slideable in a guiding member 23 and a rod 20 slideable in a guiding member 21. The rod 20 is provided with a finger 46 adapted to lift the valve by acting upon an adjustable stop piece 19. The valve is closed by the 70 spring 17 as soon as the cam 10 permits the pusher rod 22 to fall. 31 indicates the discharge valve through which the liquid fuel is delivered to the atomizer of the engine.

The shafts 1 and 2 are contained in a casing 75 24 having disposed thereon a casing 25 containing the regulating devices and having disposed thereupon the frame 26 forming the main body of the pump. Upon the said frame is secured the upper casing 27. A 80 central pin 28 serves to assemble these various parts by the use of the nuts 29 and 30, the latter being used as an oil filling plug. A fixed stop piece 65, (Fig. 1) secured to the pump body 26 is employed to prevent the 85 piston 13 from leaving its guiding member, upon dismounting the apparatus, under the action of the spring 14.

The liquid fuel is brought to the pump by means of a three-way cock 32 (Figs. 2 and 90 6) which provides for the use of two separate fuels, one being employed for starting purposes. The liquid fuel passes through a filter 33 and is admitted to the fuel chamber through a duct 34.

Upon the guiding members 12, are screwed 95 the nuts 35 having formed on their periphery suitable gear teeth cooperating with tubular racks 38 (Figs. 2 and 4) in such manner that by actuating the latter, the upper part 100 36 of the nuts is caused to approach or to recede from a flange 37 disposed upon each of the pistons 13. Within each of the racks 38 is screwed a ring 39, Fig. 4, these rings having respectively a right and left hand 105 thread and being provided with a central square aperture having respectively slideable therein by easy friction the rods 40 having a square cross section. The said rods are secured to an actuating rod 43. Shock-absorbing springs 41 are disposed on either side of the rings 39 and bear upon shoulders 110

42 formed on the rod 43. This latter rod has secured to the outer end thereof a yoke 44 which is connected with the governor.

Fig. 5 shows the cams 9 and 10 of one of the pumps on a larger scale. The cam 9 is shown in the same position as in Fig. 2, this representing the moment when the piston is about to be suddenly moved upwards—for discharge and injection—by the portion of the profile 47, 48. From the point 48 to 49 there is formed a long cylindrical portion which maintains the piston in the fixed position at the top of its stroke. During this time the cam 10, Fig. 5, which is here represented in its proper angular position with reference to the cam 9, has now gradually raised the admission valve 16 by the portions 50 to 51, by means of the above-described devices. From the points 49 to 52, the cam 9 will now provide for the descent of the piston 13 for admission purposes by the action of the spring 14. Upon the descent of the piston, the valve 16, which has been left fully opened after the point 51, will begin to close at 53 and will be entirely closed at 54, the piston 13 being again motionless from 52 to 47. The output is regulated by means of the nuts or movable stop-pieces 35. These are more or less raised or lowered by screwing or unscrewing the same upon the guiding members 12, thus stopping the pistons on their downward stroke at any point thereof by the contact between the surfaces 36 and 37. The pusher rods 11 alone will continue upon the descent under the action of the springs 55. This point will be considered in detail hereunder. In this manner all the possible amounts of stroke may be obtained between zero and the maximum accorded by the profile of the cam.

The nuts 35 are both controlled at the same time by the above-mentioned racks 38. The use of a double interior spring 41 to actuate each of the said racks is to be remarked in connection with the profile of the cams, as will be further set forth. The long cylindrical portion 48, 49 of the cam 9 will be observed. During this entire period, the piston 13 remains entirely raised, and the corresponding nut 35 is altogether relieved. For this reason, the slightest effort will suffice to move this nut. During the period from 49 to 52, 47 and 48, on the contrary, the nut 35 is—or may be according to its height—submitted to the effort of the spring 14 which presses together the surfaces 36 and 37. During this entire phase, admitting that the rod 43 connected by the yoke 44 with the centrifugal or like governor not shown, has been impelled in one or the other direction, the springs 41 will have alone been operative, one being stretched and the other compressed. Upon the subsequent passage of the portion of the cylindrical profile 48, 49, the springs 41 will now act upon the rack 38 through the

medium of the ring 39 in the desired sense. This will afford a much greater sensitiveness for the governor, which is only obliged to overcome the very slight force of the springs 41. These springs are made very weak, inasmuch as they are always called upon to act upon a member which is relieved and is very easy to move. It is obvious that this action will only take place if the screw-threaded portions 56 of the rings 35 are not of a reversible nature and are therefore not subjected to rotation under the lengthwise pressure of the spring 14, this being an absolutely essential condition.

The parts 40 having a square cross section and the right and left hand screwthreads of the rings 39 are provided for the purpose of adjustment. After disconnecting the control member from the yoke 44, the rod 43 is turned about and thereby effects the rotation of the rings 39 in the racks 38; these latter are however held against rotation by reason of their teeth being in engagement with the nuts 35. The two racks are thus separated or brought together to a greater or less degree, in order to complete the identical adjustment of the two stop pieces 35 in the vertical sense with reference of the two stop pieces 35 in the vertical sense with reference to the flange portions 37 of the pistons, this adjustment having already been approximately carried out by a suitable location of the engaging point of the interengaging teeth. In the example here shown, the rod 44 can only be rotated through half a revolution, which appears to be sufficient, especially if the screwthread of the rings 39 is very fine, but the adjustment might be carried out upon the rod 43 alone, this being rotated through any suitable angle, whereupon the yoke 44 would be screwed upon the rod 43 in a suitable position for the coupling thereof.

The shape of the cam 10 has likewise an effect in this case. It will be observed that if, as in this case, the portion 48, 49 is equal to or above one-half of the circumference, the cam shaft 2 may be so disposed that both pistons shall be in the highest position at the same time. The cover plate 57, Fig. 1 may be unscrewed, or a readily removable door may be disposed thereupon, and the said position may be rapidly ascertained by means of a suitable mark which is placed upon the end of the shaft. The rod 43 may then be adjusted by hand in order to bring the two stop-pieces 35 in contact, by means of their surfaces 36, with the flanges 37. The two contacts should take place exactly at the same time if the adjustment is well carried out, and this may be observed, and even measured if required, by the use of a guage, through the inspection cover 58, Fig. 1, of the casing 25, the said cover serving likewise for the insertion of the wrench used to

tighten the piston guide member 59 which also constitutes a packing member.

It should be observed that this method for adjusting the stop-piece by a simple rotation 5 of the rod 43 is only applicable to the case of an apparatus comprising two pumps. However, the control of all the stop pieces by means of racks combined with elastic coupling employing double springs, such as 10 41, is applicable to an apparatus comprising any number of pumps.

It is to be noted that although the cylindrical portion 48; 49 of the cam 10 is of considerable value as compared with the entire profile, it nevertheless corresponds to a very short period of time in a high speed engine. At each passage of the remaining portion of the cam, the rack is held in the fixed position. Upon each occurrence of the 20 moment at which the springs 41 are enabled to act, they are obliged to overcome the inertia of the racks 38 and the nuts 35 which they are required to actuate and which are stationary when acted upon. It is thus important that these parts be given as light a weight as possible. The nut 35 which is subject to the impact is made preferably of steel of high strength whereby a very reduced thickness may be employed. The rack 25 30 is preferably made of an alloy of aluminum, and its bore may be disposed in an eccentric position in order that the member shall have the thin portion situated on the side opposite the teeth. This member may likewise be 35 constituted by an extremely thin tube having the toothed portion formed thereon by the pressing process. In this case, a suitable piece secured within the said member, and preferably soldered would be provided with 40 the right or left hand screwthread cooperating with the rings 39.

In this device, the long cylindrical portion 48, 49 of the cam 9 is used to very good advantage from another standpoint and aside from the question of regulation. It 45 has been already remarked that the admission valve 16 is required to be entirely opened before the commencement of the downward stroke of the piston 10, this being necessary in order to prevent the accumulation of two suction effects, inasmuch as the valve itself acts as a piston, as in fact the movement of the valve head increases the internal capacity of the pump. But the conditions of the opening movement of the 50 55 valve are not indifferent. At the beginning of this operation, in fact, the flow section past the valve seat is extremely small, and hence the lifting movement should be very slow and should then gradually increase in speed. This action required the use of a considerable length of lifting profile 50, 51 which constitutes a spiral of increasing pitch, while the portion 49—52 of the cam 9

used for the descent of the piston is an 65 Archimedes' spiral.

The herein described method of adjustment might be considered as subject to a serious drawback, as it would occasion much noise; in fact when the piston 12 has been held fast at the middle point of the stroke, for instance and when the pusher rod 11 which is operating at full speed under the effect of the portion 47, 48 of the cam 10 enters in contact with the said piston at the upper end 60 of the said pusher rod, there is produced a very marked sound. This sound can however be greatly reduced by the use of the following arrangement. The nut 35 is provided with an inner chamber 35^a and a plurality of apertures 62, and on the other hand the casing 25 is made tight and is filled with a rather fluid oil. In this case, when the piston is held at a point on its down stroke by the stop piece 36 and the pusher continues its descent under the action of the spring 55 (Fig. 1), the space now formed in chamber 35^a between the corresponding surfaces 60 of the pusher and 61 of the piston will become filled with oil which has entered through the apertures 62. During the up stroke, this oil will act as a cushion for deadening the sound.

The presence of this oil of a fluid character and the use of the closed casing will likewise have an effect which is advantageous and prejudicial at the same time—but more advantageous than otherwise—as regards the regulation of the mechanical movement. It will in fact provide for a very smooth running of the mechanical parts, these being kept perfectly clean, and this easy running is of constant duration, which exerts a favorable influence upon the action of the governor, as above-stated, but on the contrary, the inertia of the liquid to be displaced must be added to that of the metal parts set in movement by the action of the springs 41, and especially of the racks. This drawback may be reduced, not only by the above-indicated use of, fluid oil which has been already recommended as affording an easy friction for the said parts working under light loads, but also by the arrangement of suitable flow sections at 63, 64 (Fig. 1) 110 around the said racks. It will be noted that a shock is also produced between the surfaces 36 and 37, but this shock, which is here considerably less, will likewise be diminished by the presence of oil.

The use of the said casing 15 filled with oil makes it necessary to employ special precautions to secure the tight working of the piston 13. The fuel must in fact be prevented from entering the casing 25 whence it might enter the casing 24. A suitable disposition is therefore employed whereby any liquid fuel which may leak through the pack-

ing member 81 (Fig. 1) shall be caused to flow out through a visible passage. To this effect, the guiding member 59 forming a packing member is provided with a shoulder 66 (Fig. 1) adapted to press an elastic washer 67 against a corresponding shoulder in the pump body 26, and on the other hand the lower end of the guiding member 59 is provided with a second packing member 68 of a more summary description which in the present example is held automatically pressed by the spring 14 itself, by the use of a suitable cap 69. The guide member 59 is likewise provided at the upper part and 15 on the interior and exterior below the packing member 65, with grooves and ducts such as 70, 71 situated opposite a duct 72 (Fig. 2) formed in the pump body in such manner as to permit the leaking oil to flow visibly 20 to the exterior into suitable cups such as 73, which may be wiped clean when required. The use of these recesses or cups 73, which are separate for each pump, will permit of ascertaining which of the packing 25 members is leaking.

It will be remarked that an appreciable advantage is afforded by a complete filling of the casings 24 and 25 with oil and by making the same perfectly oil-tight, inasmuch as 30 the liquid fuel which may have leaked out will no longer be able to enter the same, and it will be obliged to flow to the outside even if the packing member 68 and the packing 35 member 67 would be defective. A stuffing box 74 has also been provided at the end of the shaft 1, and a cup shaped leather 82 on the rod 43. A stuffing box, not shown, is also disposed at 75 about the shaft 8, and to obviate the necessity of a tight working for the guiding 40 members of the rods 20, the upper casing 27 is also made oil-tight and is also filled with oil, the whole being readily filled by the use of the stopper 30 disposed at the upper part. This latter disposition, comprising the upper 45 casing filled with oil, acts with reference to the stuffing box 76 in the same manner as has already been set forth for the joints 67 and 68.

As concerns the filling with oil, various 50 apertures of considerable size such as 77 (Fig. 3) and 78 (Fig. 4) are used to afford communication between the various levels, and smaller passages such as 79 (Fig. 3) and 80 (Fig. 4) are provided for the discharge 55 of the air from these different portions of the apparatus. These passages 77 to 80 are not located in the section planes of Figs. 1 and 2, and have not been shown for greater clearness. The passage 77 passes 60 through the main body 26; the passage 78 transverses the upper wall of the casing 24; the passage 80 starts from the casing 24 and ends at the upper part of the casing 25; the passage 79 starts from the casing 25 and ends 65 at the upper part of the casing 27.

In case the governor is simply a device for limiting the speed, and serves only as a protection against breakage or wear of the parts of the engine or the machines driven by the latter, it may not be absolutely necessary to make use of the double springs 41. The regulator may be so designed as to exert its effect upon the nuts 35, even should these be under load, but rather considerable variations in speed would be necessary in order 70 to obtain the force required to operate the nuts 35 under these conditions. Such speed variations, which would be prohibitive in the case of an electrical generator group, for instance, will have no importance in the case 75 of a motor vehicle. For this latter use, the governor comprises, as is well known, a device which is under the control of the driver for obtaining at will all the speeds below 80 maximum speed.

As above stated, the adjustment of the point of injection, which is much simpler than that of the output, is obtained by actuating the fork 8 by the lever 45 which is operated by hand. It is obvious that this device would also be acted upon a centrifugal or like governor, and in this case it would be possible to replace all the lead adjustment mechanism as above described by an automatic mechanism working according to the speed, this being of the well known type such as is used for a like purpose upon magnetos for internal combustion engines with variable speed.

It is understood that this invention is not 100 limited to the constructional details hereinbefore set forth.

Having now described my invention, what I claim as new and desire to secure by Letters Patent is:

1. A pump for injecting liquid fuel for internal combustion engines comprising a pump body, a piston movable in said pump body, a rotary driving shaft, a cam on said shaft for actuating the piston in its discharge stroke, a spring for actuating the piston in its suction stroke and an adjustable stop member for limiting the suction stroke of the piston, the cam having its maximum diameter over a portion extending 110 at least about half the circumference whereby the piston is lifted and the adjustable stop member is relieved for a considerable part of each revolution of the cam.

2. A pump for injecting liquid fuel for 115 internal combustion engines comprising a pump body, a piston movable in said pump body, a rotary driving shaft, a cam on said shaft for actuating the piston in its discharge stroke, a spring for actuating the 120 piston in its suction stroke, a supporting member, a nut screwed upon said supporting member and forming an adjustable stop for limiting the suction stroke of the piston, a rack in engagement with gear teeth formed 125

on said nut and means for operating said rack.

3. A pump for injecting liquid fuel for internal combustion engines comprising a pump body, a piston movable in said pump body, a rotary driving shaft, a cam on said shaft for actuating the piston in its discharge stroke, a spring for actuating the piston in its suction stroke, a supporting member, a nut screwed upon said supporting member and forming an adjustable stop for limiting the suction stroke of the piston, a rack in engagement with gear teeth formed on the nut, control means for operating said rack and springs affording a yielding connection between said rack and the control means.

4. A pump apparatus for injecting liquid fuel for internal combustion engines, comprising two pump bodies, two pistons movable in said pump bodies respectively, a rotary driving shaft, cams on said shaft for actuating the pistons in their discharge stroke, respectively, springs for actuating the pistons in their suction stroke, respectively, supporting members, nuts screwed upon said supporting members respectively and forming adjustable stops for limiting the suction stroke of the pistons, racks respectively in engagement with gear teeth formed on said nuts, screwthreaded rings screwed in said racks, respectively, a control rod having parts of polygonal cross section which extend through said screwthreaded rings, and springs on both sides of said screwthreaded rings and bearing upon shoulders on said control rod.

5. A pump for injecting liquid fuel for internal combustion engines comprising a pump body having a pump chamber therein a piston movable in said pump chamber, a lower casing below said pump body, a rotary driving shaft mounted in said lower casing, a cam on said shaft, a pusher rod operatively connecting the piston and the cam, guiding means for said pusher rod, an intermediate casing containing said guiding means, a spring for actuating the piston in its suction stroke, said spring being arranged in said intermediate casing, a fuel chamber in the pump body above the pump chamber and an upper casing on the pump body above said fuel chamber, said upper

intermediate, and lower casings being filled with oil, and means affording a communication between said casings. 55

6. A pump for injecting liquid fuel for internal combustion engines comprising a pump body having a pump chamber therein a piston movable in said pump chamber, a lower casing below said pump body, a rotary driving shaft mounted in said lower casing, a cam on said shaft, a pusher rod operatively connecting the piston and the cam, guiding means for said pusher rod, an intermediate casing containing said guiding means, a spring for actuating the piston in its suction stroke, said spring being arranged in said intermediate casing, a fuel chamber in the pump body above the pump 70 chamber and an upper casing on the pump body above said fuel chamber, said upper intermediate and lower casings being filled with oil, means affording a communication between said casings, means forming an oil 75 chamber in the intermediate casing around the point of impact between the pusher rod and the piston and means affording a restricted communication between the said oil chamber and the intermediate casing. 80

7. A pump for injecting liquid fuel for internal combustion engines, comprising a pump body having a pump chamber therein, a piston movable in said pump chamber, a lower casing below said pump body, a rotary driving shaft mounted in said lower casing, a cam on said shaft, a pusher rod operatively connecting the piston and the cam, guiding means for said pusher rod, an intermediate casing containing said guiding 85 means, a spring for actuating the piston in its suction stroke, said spring being arranged in said intermediate casing, a fuel chamber in the pump body above the pump chamber and an upper casing on the pump 90 body above said fuel chamber, said upper intermediate and lower casings being filled with oil and means affording a communication between said casings, ducts being provided in the pump body to direct to the outside the fuel which may leak around the piston. 100

In testimony whereof I have signed my name to this specification.

EUGÈNE HENRI TARTRAIS.
